HYDRAULIC PUMP UNLOADER.
APPLICATION FILED APR. 11, 1917.

Patented May 28, 1918.

2 SHEETS—SHEET 2.

UNITED STATES PATENT OFFICE.

LEONARD A. VIGNERI, OF PITTSBURGH, PENNSYLVANIA.

HYDRAULIC PUMP-UNLOADER.

1,267,720.

Specification of Letters Patent. Patented May 28, 1918.

Application filed April 11, 1917. Serial No. 161,182.

To all whom it may concern:

Be it known that I, LEONARD A. VIGNERI, a citizen of the United States, and a resident of the city of Pittsburgh, in the county 5 of Allegheny and State of Pennsylvania, have invented certain new and useful Improvements in Hydraulic Pump-Unloaders, of which the following is a specification.

My invention relates to a hydraulic unloading device adapted for use in connection with a fluid pressure pump discharging into an accumulator wherein it is desired that the discharge of fluid from the pump to the accumulator shall be controlled either manually 10 or automatically without affecting the operation of the pump. More specifically, it relates to an unloading device wherein the unloading action is produced by effecting a communication or by-passing through the 15 unloading device between the discharge and suction manifolds of the pump. In use in connection with accumulators in hydraulic work, such as those for operating hydraulic presses, riveting machines, hammers, etc., my unloading device offers a means for automatically 20 regulating the stroke thereof, the unloading device causing the pump to run light or without discharging into the accumulator when the latter has reached the predetermined limit of its stroke, and maintaining the pump in this condition until the 25 return of the accumulator to a predetermined point.

The objects of my invention are to provide 30 an unloading device for pumps discharging into an accumulator which may be readily interposed in the pump circuit by connection of the intake and discharge manifolds of the pump which will effect the unloading of the pump positively and freely 35 at the predetermined moment, and which will eliminate shocks on the valves of the pump on resumption of load by the latter. Further objects of my invention will hereinafter appear.

In accordance with my invention I provide 40 in an unloading device means for cutting off the supply of water or fluid to the pump simultaneously with the by-passing of the water or fluid from the discharge to the 45 suction manifold of the pump, thereby equalizing the pressure on the valves of the pump and eliminating shocks thereupon when the pump is again loaded.

An embodiment of my invention is illustrated in the accompanying drawings, wherein—

Figure 1 is a somewhat diagrammatic representation in elevation of the unloading device and its connections with a pump and an accumulator, shown in this instance as a hydraulic press.

Fig. 2 is a longitudinal section through the unloading device, and

Fig. 3 is a transverse section therethrough at right angles to Fig. 2.

The unloading device, 5 is connected upon one hand, to the suction and discharge manifolds 6 and 7, respectively, of the pump 8, and on the other hand to the water supply pipe 9, and to pipe 10 discharging to the accumulator 57.

The intake 11 of the unloading device itself divides into two portions 12 and 13 in order to pass around the operating cylinder 14 for the by-pass valve operating mechanism, these passages joining each other to form the passage 15 which opens into the suction passage 16, to which the suction manifold 6 of the pipe connects. A 80 check valve 17 is provided at the point at which the passage 15 opens into the suction passage 16, this valve, in the embodiment shown comprising a facing of alloy, babbitt or the like 18, a stem 19, and a spring cap 20, and being retained against the seat 21, which is formed as a spider with a central guide for the valve stem 19, by spring 22 surrounding the stem 19 and retained within the cap 20. The suction passage 16 is provided with a removable plate or the like 23, whereby access to the check valve may be had.

The suction passage 16 also connects with the discharge passage 24 through opening 95 25, this opening being closed when the pump is running under load by means of by-pass valves. These by-pass valves are, in the embodiment shown, two in number and consist of a main by-pass valve 26 seated upon the 100 opening 25 and provided with suitable Babbitt or alloy facings, if desired, and with openings or holes 28 passing entirely therethrough, and an auxiliary or pilot by-pass valve 29 which rests upon the main by-pass 105 valve 26 and closes the holes 28 therein on normal operation of the pump under load. Both by-pass valves are mounted upon a

valve stem 30, the auxiliary or pilot by-pass valve retained between a shoulder 31 and a lock nut 32, the latter also being utilized as a means for regulating the lift of the valve.

5 The main by-pass valve is mounted upon the valve stem 30 below the shoulder 31, a second shoulder 33 being provided at a distance below the shoulder supporting the auxiliary by-pass valve 29 somewhat greater than the 10 thickness of the main by-pass valve 26 so as to permit of a slight movement of the valve stem 30 in the upward direction before lifting the valve 26.

The valve stem 30 passes upward through 15 the top of the passage 24, and through a suitable stuffing box 34, and terminates in a spring cap 35. This cap is surrounded by a yoke 36 provided with a regulating screw 37, to which is attached a second spring cap 20 38 opposite the spring cap 35. A spring 39 is placed between the two spring caps 35 and 38 and tends constantly to force the valve stem 30 downwardly and to maintain the by-pass valves 26 and 29 seated. The 25 force with which the spring 39 acts may be regulated by means of the screw 37, locked by a lock nut 40.

Below the by-pass valves 26 the valve stem 30 passes downwardly through the suction passage 16 and the stuffing box 41 into the operating cylinder 14, in which it terminates in piston 42, which is normally positioned near the bottom of the operating chamber 14 when the by-pass valves are 30 closed. In the specific embodiment shown this piston comprises a body 43, a cup leather 44, a follower 45 and a spring 46, the whole being united by lock nut 47.

The bottom of the operating cylinder 14 40 is closed by a head 48 provided with a channel 49 communicating with the interior of the cylinder and with an intersecting channel 50. A three-way valve 51 is also provided which in one extreme position cuts 45 off the passage 49 and makes connection between the passage 50 and the upper portion of the passage 49 and which in the other extreme position closes the channel 50 and opens the channel 49. The channel 50 is connected to a water inlet pipe 52 and the end 50 of the channel 49 is connected to the water outlet or discharge pipe 53. The three-way valve 51 is operated by means of lever 54. The movement of this valve may be effected 55 in any suitable manner. As illustrated in Fig. 1, movement in one direction, namely that opening the outlet 53 to the passage 49, may be effected by a weight 55, and in the other direction by means controlled by the 60 accumulator 57, illustrated as a cable 56 provided with suitable pulley arrangements and connected to the lever 54 in such manner that on the plunger rising to a predetermined point, stop 58 on the cable operates the lever 65 54 and the valve 51 to effect unloading and

on dropping to another predetermined point the lever and valve are operated in the opposite direction by stop 59.

The manner in which my unloading device is connected in the system with the water supply, the pump and the discharge from the pump to the accumulator has already been described. In operation, when the pump is discharging through the discharge passage 24 of the unloading device to the 70 accumulator, the by-pass valves 26 and 29 are maintained in the closed position by the spring 39, the piston 42 being approximately at the bottom of the cylinder 14, and water enters freely through the passages 11, 12, 13, 80 15 and 16, check valve 17 permitting free passage thereof. A normal intake and discharge by the pump is thus permitted. This discharge, passing to the accumulator, finally brings the latter to the predetermined final 85 position at which operation of the lever 54 and the three-way valve 51 is effected. Valve 51 is then partially rotated to permit communication of passage 50 with the upper portion of passage 49 and to cut off discharge 90 into discharge pipe 53. Water then enters from the inlet pipe 52, passing into the operating cylinder 14 below the piston 42, tending to force the latter upwardly against the action of the spring 39. The 95 auxiliary by-pass valve 29, being rigidly attached to the valve stem 30, moves upwardly with the latter under the action of the water under piston 42, while the main by-pass valve 46 is held in position by the water pressure 100 in passage 24, being allowed a limited amount of free movement before being engaged by the shoulder 33 on the valve stem 30. The 105 upward movement of auxiliary by-pass valve 29 relative to the main by-pass valve 26 opens the ports or holes 28 in the latter and thereby permits equalization of the water pressure 110 on both sides of the by-pass valve and facilitates its movement by the continued upward movement of the valve stem 30, effected by 110 the continued influx of water in the bottom of the cylinder 14.

As a result of the opening of the by-pass valves 26 and 29, communication is effected 115 through the opening 25 between the discharge passage 24 and the suction passage 16. The higher pressure of the fluid in passage 24 causes its flow into the passage 16, forces the check valve 17 to close, thereby cutting off intake of water from the passages 11, 12, 13 and 15, and effecting a closed path 120 of circulation between the discharge and suction manifolds of the pump. The latter continues to operate, the water, however, flowing in a closed path through the passages 24, 125 25 and 16 in the unloading device and through the pump itself, thus equalizing the pressure on both the suction and discharge valves in the pump and preventing shocks on resumption of its load. In reverse opera- 130

tion, when the accumulator, press plunger or the like has reached its other extreme position and it is desired that the pump resume its load, valve 51 is rotated to open the passage 49 and to cut off passage 50, thereby permitting the water in the operating cylinder to discharge. The spring 39 then forces the valve stem 30 and piston 42 downwardly, closes the by-pass valves 26 and 29, and the continued action of the pump once more causes the intake of water through the check valve 17 and discharge into the accumulator through the passage 24.

As is readily apparent from the drawings, my device may be constructed in such a manner as to be easily manufactured and repaired. In the embodiment illustrated, it is formed of a plurality of relatively simple castings, securely held together by suitable 20 studs or bolts and of such design as to be readily removable and reparable. It is obvious that the precise form and design of the construction is not of the essence of my invention, but that these may be varied within 25 such limits as will be readily apparent to any person skilled in the art.

I claim:

1. In an unloading device for fluid pumps, means for shutting off supply of fluid to the intake of the pump and means for diverting the discharge from the pump to its intake.

2. In an unloading device for fluid pumps, a supply passage for supplying fluid to the intake of the pump, means for diverting the discharge from the pump to its intake and for thereby effecting closure of the supply passage.

3. In an unloading device for fluid pumps, a supply passage for supplying fluid to the intake of the pump, means for diverting the discharge from the pump to its intake, and a check valve adapted to close said supply passage when said diversion takes place.

4. In an unloading device for fluid pumps, a suction passage intended to communicate with the intake of the pump, a discharge passage intended to communicate with the discharge of the pump, a supply passage communicating with the suction passage, means for effecting communication between the discharge and supply passages and check valve adapted to close said supply passage when such communication is effected.

5. In an unloading device for fluid pumps, a suction passage intended to communicate with the intake of the pump, a discharge passage intended to communicate with the discharge of the pump and with an accumulator, the suction passage opening

into the discharge passage, a by-pass valve mechanism normally closing off the suction passage from the discharge mechanism, a supply passage communicating with the suction passage and a check valve adapted to close off said supply passage when the by-pass valve is opened.

6. In an unloading device for fluid pumps, a suction passage intended to communicate with the intake of the pump, a discharge passage intended to communicate with the discharge of the pump and with an accumulator, the suction passage opening into the discharge passage, by-pass valve mechanism for closing off the suction passage from the discharge mechanism, means for normally retaining said by-pass valve mechanism in the closed state, means for opening said by-pass valve mechanism, a supply passage communicating with the suction passage and a check valve adapted to close off said supply passage when the by-pass valve is opened.

7. In an unloading device for fluid pumps, a suction passage intended to communicate with the intake of the pump, a discharge passage intended to communicate with the discharge of the pump and with an accumulator, the suction passage opening into the discharge passage, by-pass valve mechanism for closing off the suction passage from the discharge mechanism, said by-pass valve mechanism comprising a main by-pass valve provided with by-pass ports and an auxiliary by-pass valve operatively connected thereto and closing said by-pass ports, means for normally maintaining said by-pass valve mechanism closed, means for opening the auxiliary by-pass valve and subsequently opening the main by-pass valve, a supply passage communicating with the suction passage and a check valve adapted to close off said supply passage when the by-pass valve mechanism is open.

8. In an unloading device for fluid pumps, a suction passage intended to communicate with the intake of the pump, a discharge passage intended to be interposed between the discharge of the pump, and an accumulator, the suction passage opening into the discharge passage, by-pass valve mechanism for closing off the suction passage from the discharge mechanism, a spring normally closing the by-pass valve mechanism, a hydraulic plunger for opening said by-pass valve mechanism, means for operating the hydraulic plunger controlled by the accumulator, a supply passage communicating with the suction passage and a check valve adapted to close off said supply passage when the by-pass valve is opened.

LEONARD A. VIGNERI.
